UNITED STATES PATENT OFFICE.

ALFRED O. BAILEY, OF NEW YORK, N. Y., ASSIGNOR TO GOLD CAR HEATING & LIGHTING COMPANY, OF NEW YORK, N. Y., A CORPORATION OF NEW YORK.

ELECTRIC HEATER.

1,147,917.

Specification of Letters Patent. Patented July 27, 1915.

Application filed September 12, 1914. Serial No. 861,373.

To all whom it may concern:

Be it known that I, ALFRED O. BAILEY, a citizen of the United States of America, residing in the borough of Brooklyn, county 5 of Kings, city and State of New York, have invented certain new and useful Improvements in Electric Heaters, of which the following is a specification.

My invention relates to electric heaters, 10 and particularly to the casings wherein such heaters are contained, and it relates to that type of such heaters as is customarily employed in the heating of railway or trolley cars.

15 My invention has for its object to provide an improved construction of such casing the interior of which is easily accessible for the purpose of facilitating the removal or repair of any of the heating elements therein, and thereby increasing the usefulness of 20 the car to the railroad by diminishing the time when the said car is out of commission by reason of being withdrawn from service for repairs to the heater.

25 My invention is particularly useful in the heating of railway passenger or trolley cars, wherein the car seats are provided with removable cushions. This is an ordinary type of construction and it includes the most expensive cars in service, the removal of which 30 from service for the purpose of repairing the heaters is a serious loss to the railroad.

In the accompanying drawing Figure 1 is 35 a plan view, partly broken, of a casing constructed according to my invention, and Fig. 2 is a section on the line 2—2 of Fig. 1, showing the car seat.

In carrying my invention into effect the 40 casing, which as a whole, is designated A, is provided with a base or body portion B, and with a removable cover portion C, the edges of which preferably fit snugly over the body portion B so that the same may be held together. As illustrated these parts 45 are assembled by sliding together. These parts of the casing A are preferably perforated as at b, c, to provide for the emission of heat provided by the heater therein contained, which is illustrated as an electric 50 heater, this being the type of heater usually employed.

In order that the heat furnished by the 55 heater within the casing A may not disagreeably affect the cushion D of the car seat and the passenger thereon, I provide a

shield F and interpose the same between the cover C and the cushion D. This shield F not only serves the function of shielding the occupants of the car seat E from the direct effects of the heat, but likewise has a very 60 useful function in enabling the cover of the casing to be easily taken off for the purpose of getting at the heater therein. For this purpose the shield F is preferably connected to the cover C, and a convenient means of 65 accomplishing this is by riveting the same together as at G. Therefore when the car seat D is removed from its position the lifting of the shield F will cause the removal of the removable cover C enabling the base 70 or body part B to be inspected and desired repairs made thereon, or the heaters to be removed therefrom if desired.

A convenient way in which the heater may 75 be supported is by means of brackets H, of which two are illustrated. These pass directly under the body part B and have supports upon the seat frame I. As illustrated, these seat frames are angle irons, and a support is provided by causing the bent ends h 80 of the bracket to rest upon the angle irons, where they are held in position by bolts J and nuts j. For the purpose of securing the parts fixedly in position it is quite desirable that the shield F should be held rigidly in 85 place, and accordingly the same is perforated near the sides to receive the bolts J which are held therein by nuts j¹. This enables the shield and cover C to be removed without disturbing the base B. 90

The car seat E is illustrated in the conventional way, as the types to which references are made are very well known. Frequently these car seats extend crosswise of the car, and often they extend lengthwise of 95 the car. My invention may be used with either kind.

I have illustrated electric heaters in place in my improved casing, but my invention is not concerned with the construction of such 100 heaters. The heaters are illustrated as supported upon end blocks K having ledges k k¹, upon which are mounted spring clips L L¹ to receive the ends of the heater unit M.

The construction of the blocks K are not 105 claimed herein, but form the subject of a separate application, filed by me August 6, 1914, Serial No. 855,351. Also the construction of spring retaining clips for the heating unit M is not claimed herein, but forms 110

the subject of a separate application filed by F. T. Kitchen, August 28, 1914, Serial No. 859,054.

The heater herein illustrated is an electric heater wherein the leading-in wire N is connected to the spring clip L¹, and the current is passed therethrough to a contact band m upon the end of the heater M which is in electrical connection with the resistance wire m¹. This wire is electrically connected to a core m² by which the current is returned through clip L to the return wire O. My invention, however, is not concerned with the type of heater shown, nor with the manner of connecting the wires, nor with the way of supporting the heaters in the casing, but it has reference to the construction of the casing and the provision of simple and convenient means whereby the interior of the heater may be readily gotten at. It will therefore be perceived that my invention is not limited to the precise means illustrated of supporting the casing, nor to the particular type of heater employed therein, as any type of heater may be employed, and various modifications may be made in the construction of the casing within the limits of the appended claims.

What is claimed is:—

- 30 1. A casing for an electric heater comprising base and cover parts, means for supporting the base, the cover part adapted to be applied to the base and to be removed therefrom to close and open the casing and a shield connected to the cover part and adapted when removed from position to carry the cover with it.
- 25 2. An electric heater casing comprising separable perforated base and cover parts, brackets for supporting the base from a car-seat frame, and a shield connected to the cover.
- 35 3. An electric heater casing comprising a perforated base, a bracket for supporting same from a car-seat frame, a removable cover and a shield connected to the cover so that the cover is removable with the shield, and a connection between the shield and a car-seat frame.
- 40 4. In combination a car-seat frame, a removable car-seat thereon, and an electric heater casing disposed below said car-seat comprising a base portion supported from

the car seat frame and a removable cover portion, said casing being accessible through the car-seat frame when the car seat is removed.

5 5. In combination a car-seat frame, a removable car-seat thereon, and an electric heater casing disposed below said car-seat comprising a base portion, a bracket connected thereto and to the car-seat frame, and a removable cover portion, said casing being accessible through the car-seat frame when the car-seat is removed.

6 6. In combination a car seat comprising a frame and a removable cushion, a heater casing located below said car-seat and comprising separable base and cover parts, a supporting connection between the frame and the base, and a shield interposed between the cover and the cushion and a connection between said shield and the car-seat.

7 7. In combination a car-seat comprising a frame and a removable cushion, a heater casing having a base portion and a separable cover, a bracket connecting the base to the frame, a shield connected to the cover and interposed between the same and the cushion.

8 8. In combination a car-seat having a removable cushion and a heater disposed below said cushion having a casing comprising a removable cover and a shield connected to said cover and interposed between the same and the cushion.

9 9. In combination a car-seat having a removable cushion and a heater disposed below said cushion having a casing comprising a removable cover and a shield interposed between said heater and said cushion.

10 10. In combination a car-seat having a removable cushion and a heater horizontally disposed and located beneath said cushion having a separable casing comprising a fixed base and a removable cover, a shield connected to the cover so as to carry the cover with it when it is removed, and interposed between the seat and the heater.

In witness whereof, I have hereunto signed my name in the presence of two subscribing witnesses.

ALFRED O. BAILEY.
